FOUNTAIN BRUSH FOR APPLYING ADHESIVE OR THE LIKE

Charles O. Kilham, Beverly, Mass.

Application February 20, 1958, Serial No. 49,717

Term of patent 7 years

(Cl. D9—2)

Fig. 1 is a view in side elevation of a fountain brush for applying adhesive, embodying my new design, the hose portion being fragmentarily shown for convenience of illustration only;

Fig. 2 is an elevational view thereof as seen from the bottom of Fig. 1;

Fig. 3 is a perspective view of the fountain brush as seen from the side and rear with a portion of the hose shown broken away to indicate indeterminate length; and

Fig. 4 is a view in front end elevation of the brush.

I claim:

The ornamental design for a fountain brush for applying adhesive or the like, substantially as shown.
